[57] CLAIM

The ornamental design for a printer table, as shown and described.

DESCRIPTION

FIG. 1 is a perspective view of a printer table showing my new design;

FIG. 2 is a top plan view;

FIG. 3 is a front elevational view;

FIG. 4 is a right side elevational view, the left side being a mirror image thereof;

FIG. 5 is a bottom plan view; and,

FIG. 6 is a rear elevational view thereof.
